DESIGN FOR A SHOE

Leon E. Golden, Baltimore, Md., assignor to Cannon Shoe Company, Baltimore, Md., a corporation of Massachusetts

Application November 5, 1934, Serial No. 53,886

Term of patent 3½ years

To all whom it may concern:

Be it known that I, Leon E. Golden, a citizen of the United States, residing at Baltimore, in the county of Baltimore and State of Maryland, have invented a new, original, and ornamental Design for a Shoe, of which the following is a specification, reference being had to the accompanying drawing forming a part thereof.

I claim:

The ornamental design for a shoe as shown.

LEON E. GOLDEN.
